UNITED STATES PATENT OFFICE.

EDWARD T. GILMORE, OF WESTBOROUGH, MASSACHUSETTS.

IMPROVEMENT IN BED-BOTTOMS.

Specification forming part of Letters Patent No. 126,801, dated May 14, 1872.

To all whom it may concern:

Be it known that I, EDWARD T. GILMORE, of Westborough, in the county of Worcester and State of Massachusetts, have invented a new and useful Improvement in Spring-Beds; and I do hereby declare the following to be a full, clear, and exact description thereof, which will enable those skilled in the art to make and use the same, reference being had to the accompanying drawing forming part of this specification, in which drawing—

Figure 1 represents an end view of my invention, partly in section. Fig. 2 is a longitudinal vertical section of the same.

Similar letters indicate corresponding parts.

This invention consists in the arrangement of tension-spring levers bearing on the corners of the webbing which forms the connection between the slats and heli-conical springs in such a manner that, by the action of said tension-spring levers, the webbing is always kept tight, the heli-conical springs are retained in an upright position, and the end slats are prevented from assuming an outwardly-inclined position when the bed is used, thereby preserving the full width of the bed in an effective state. With the heli-conical springs, tension-spring levers, and the slats, are combined cylindrical plugs provided with grooves or recesses just large enough to receive the small ends of said springs, in such a manner that when the plugs are secured to the slats and the small ends of the springs are sprung into their recesses a firm connection is produced between the slats and the spring in a simple, cheap, and durable way.

In the drawing, the letter A designates the frame of my bed-bottom, the transverse bars *a* of which form the supports for the heli-conical springs B. These springs are connected at their top ends by a piece of webbing, C, which is secured to the traverses *a*, and this webbing is exposed to the action of tension-

spring levers *b*, which are secured to the traverses, and bear against the webbing just beyond the end springs B, as shown in Fig. 1. By the action of the tension-spring levers the webbing is kept taut, and the heli-conical springs are prevented from tipping over. The outer ends of the springs-levers *b* are or may be provided with friction-rollers, to reduce the wear of the webbing. On the heli-conical springs B are placed the slats D, and if a person lies down on the bed the end slats are prevented from assuming an outwardly inclined position, since the tension-spring levers *b* turn their outer edges up, and thereby the full effective area of the bed is preserved. If the tension-spring levers are omitted the end slats incline outward, and the effective area of the bed is reduced by the full width of the two end slats. The connection between the slats D, the webbing C, and the heli-conical springs B, is effected by means of plugs *c*, which are fastened to the slats by nails, screws, or other suitable means, the webbing being placed between them and the slats. These plugs are provided with recesses *d* just large enough to receive the small end coils of the springs B. If these end coils are sprung into the recesses of the plugs a firm connection is effected between the slats and the springs, and, if desired, the springs can be readily disconnected.

What I claim as new, and desire to secure by Letters Patent, is—

1. The tension-spring levers *b*, in combination with the webbing C and slats D, substantially as described.

2. The combination of the springs B, tension-spring levers *b*, and plugs *c*, slats D, and webbing C, arranged and operating substantially as described.

EDWARD T. GILMORE.
